UNITED STATES PATENT OFFICE.

EDWARD C. NEWCOMB, OF SCITUATE, MASSACHUSETTS, ASSIGNOR, BY MESNE ASSIGNMENTS, TO STANDARD STEAM CORPORATION, OF ST. LOUIS, MISSOURI, A CORPORATION OF DELAWARE.

STEAM-GENERATING PLANT.

Application filed April 1, 1920. Serial No. 370,365.

To all whom it may concern:

Be it known that I, EDWARD C. NEWCOMB, a citizen of the United States, residing in the town of Scituate, county of Plymouth, and State of Massachusetts, have invented new and useful Improvements in Steam-Generating Plants, of which the following is a specification.

This invention relates to steam generating plants of the general type in which a liquid fuel is automatically supplied to a burner and water is in a like manner supplied to a generator, and means are provided for automatically controlling the fuel and water feeds.

My invention relates particularly to a steam generating plant for automobiles in which a flash, or semi-flash boiler is employed; although the invention might equally well be applied to a boiler of the water level type. In installations of this character it has heretofore been proposed to drive the water pump for supplying water to the generator, from an electric motor, which also operates a fan for supplying the air to produce and support combustion; or to drive the pump from the engine driving the car; or to employ a plurality of pumps, one of which is driven by an electric motor, and the other by the steam engine which drives the car, automatic means being provided for causing a joint or independent operation of the pumps as generator conditions may require.

In the case of electrically driven pumps an objection exists in the fact that any increase in the size and power of the car necessitates a considerable increase in the size of the electrical generating unit, and in high powered cars the size, weight and cost of the necessary electrical installation for pumping the water to the generator renders the use of a motor driven pump highly objectionable. On the other hand, where the pump is driven from the engine of the car an additional load is placed on the engine and it is difficult to co-ordinate the operation of the engine with the requirements of the steam generator under all conditions.

It is the general object of the present invention to provide a novel generating system in which the water pump is driven by

steam from the generator entirely independently of the engine driving the car.

Stated more in detail, objects of the invention are to provide a steam generating system of the character described in which the blower which supplies the air for the purposes of combustion and which is operated simultaneously with a fuel pump by an electric motor, and the water pump which supplies water to the generator, are automatically controlled by generator conditions; to provide, in a steam generating system of this character means for automatically controlling in unison the fuel supply and the water supply, where the latter is produced by means other than the motor for the fuel supply or the engine of the car; in a system having the relation of parts as last recited, to provide for the control in unison of the fuel supply and the water supply by a magnet switch which is responsive to generator conditions; to provide means whereby the fuel pump may be utilized to pump water to the boiler, as where it is considered desirable to fill the tubes of the boiler with water before placing the system as a whole in operation; to provide means in a steam generating system of the character described whereby the feed of the fuel may be cut out without interfering with the operation of the water pump which supplies water to the generator; in a system such as described to provide means whereby the pump may be operated independently of the motor which supplies the fuel for combustion; and, finally, to provide in a steam generating system of the character described, an installation involving an electric motor for supplying air and fuel for the purposes of combustion, a water pump operated independently of said motor, or of the engine driving the car and means for controlling and co-ordinating the operation of said motor and pump according to the requirements of the generator conditions.

My invention is illustrated in the accompanying drawing which is a view illustrating, to a large extent diagrammatically, a generating system according to my invention, the steam generator, the magnet switch for controlling the operation of the motor and water pump, and the solenoid valve for con-

trolling the feed of the fuel, being shown in section, and other parts being shown in plan or elevation.

Referring now to the drawing, the numeral 1 indicates a generator which is of the general type heretofore patented to me and involves the specific construction embodied in the combustion system patented to L. L. Scott, March 23, 1920, No. 1,334,560. The numeral 2 indicates a motor which operates a blower 3 and a fuel pump 4, these parts having a common shaft 5. The blower supplies air to the interior of a distributing drum 6 on the top of the generator, whence it passes through a spout 7 into the combustion chamber of the generator, supporting combustion of a flame which has been produced in the ignition chamber 8 by means of a spark plug 9. The fuel pump 4 draws fuel through a fuel-suction pipe 10 which leads from a suitable source of fuel supply, and delivers the fuel through a pipe 11 to a spray nozzle 12 under pressure, the latter spraying the fuel into the ignition chamber 8 as before stated. The fuel pump is connected by a pipe 13 with the chamber of a casing 14 with which communicates the pipe 11. The opening of this pipe is controlled by a valve 15 under the pressure of a spring 16 supported on the top of the core 17 working in a solenoid 18, these parts constituting a solenoid valve. In the length of the pipe 11 is located a joint 19 with which connects a pipe 20 leading from the fuel pump 4 and a pipe 21 leading to the Bourdon tube 22 of a fuel pressure gauge.

It is one of the objects of the invention to enable the fuel pump 4 to be utilized for supplying water to the generator. To this end a water pipe 23 leading from a suitable source of water supply is connected with the pipe 13 and is provided with a valve 24. Between the pipes 10 and 23 the pipe 13 is provided with a valve 25. In like manner a water discharge pipe 26 is connected with the pipe 20 and is provided with a valve 27. A valve 28 is provided in the pipe 13 between the pipe 26 and the joint 19. When it is desired to utilize the fuel pump 4 for pumping water the valves 25 and 28 are closed to prevent the suction of fuel by the pump on the one hand, and the delivery of water to the fuel line on the other, and the valves 24 and 27 are open, so that in operation water will be drawn up through the pipe 23 and delivered through the pipe 26. The latter pipe would ordinarily lead to and be connected with the coils of the generator, and the fuel pump 4 would be operated as a water pump when it was desired to supply the generator coils with water before placing the combustion system as a whole in operation; or, of course, under any other conditions where it might be desired to pump water to the tubes of the generator without

the occurrence of combustion. The numeral 29 indicates the steam line, that is, the pipe for conveying steam from the generator to the engine which drives the car, and located in the length of this pipe is a chamber 30 into which projects a mercury tube 31 connected with a Bourdon tube 32 of a steam temperature gauge 33. The numeral 34 indicates a battery which supplies current for the motor 2, the solenoid 18 and a magnet switch 35, to be later referred to. The numeral 36 indicates a hand operated switch which when closed, is adapted to place the entire system in operation. The solenoid 18 is normally in the circuit of the battery through leads 18^a and 38^a. When the circuit is closed at the switch 36 current will normally pass through the coil 18 and hold the core 17 in the raised position shown, whereby the spring 16 will press the valve 15 against the opening of the pipe 11. In the event the temperature of the steam in the chamber 30 should increase beyond a given degree, say 800° F., the construction is such that a contact piece 37, connected to ground at 37^a and operated by the Bourdon tube 32, will break contact with a member 38 connected by wire 38^a with solenoid 18, and thereby break the circuit of the coil 18 and permit the core 17 to drop, thereby releasing pressure on the spring 16. When this occurs the valve 15 will fall away from the end of the pipe 11 allowing the fuel to be by-passed to the suction side of the pump 4 instead of being forced to the spray nozzle 12. This interrupts the supply of fuel and no more fuel can be supplied to the burner until the temperature has decreased sufficiently for the Bourdon tube 32 to resume its normal position and thereby re-establish the circuit through the coil 18 and allow the latter to be again energized to raise the core 17. This operation is fully set forth in the patent to Scott above referred to and need not be more particularly described, as in itself it forms no part of this invention.

Leading from the chamber 30 is a steam pipe 39 which communicates with a Bourdon tube 40 of a steam pressure gauge.

The steam pressure gauge is of the construction shown in the application of Allen C. Staley, Serial No. 317,496, filed August 14th, 1919, and comprises an electromagnet 41, a pair of arms 42 and 42^a pivotally connected at 43, and constituting a movable contact member normally held upward, when in operation, by the magnet 41. Below the pivotal connection of the arms is a fixed stop 44 which limits the downward movement of the arms when the magnet is de-energized. The numeral 45 indicates a fixed contact member which is adapted to be engaged by the outer end of the arm 42^a, and the latter is adapted to be lifted out of engagement with said contact member.

against the resistance of a spring by a pin 46; on the end of the Bourdon tube 40, when the pressure of the steam exceeds a given amount, say, 600 pounds. When this occurs the circuit to the magnet 41 is broken and the arms 42 and 42^a drop at their pivotal connection 43 against the stop 44, thereby increasing the distance the end of the arm 42^a will have to move to again make connection with the fixed contact 45. The arm 42 is pivotally mounted on a fixed pivot at 47, and on this pivot is also pivotally mounted an arm 48; the outer end of which engages a fixed contact member 49. The arm 48 is adapted to be raised against resistance of the spring by a pin 50 on the end of the Bourdon tube 22 of the fuel pressure gauge, when the pressure of the fuel exceeds a given degree, say, twenty pounds. When the arm 42^a, under the influence of steam pressure, is raised out of engagement with the contact 45, the circuit to the magnet switch 35; to be later referred to, will be broken and, in the particular embodiment of the invention shown, both the motor 2 and the water pump, for supplying water to the generator, will be put out of operation, as will appear more clearly from the description of the devices mentioned, which will now be given.

The numeral 51 indicates, generally, a water pump, comprising a steam cylinder 52 and a pump cylinder 53 having a common piston rod 54. Secured on the piston rod 54 is an arm 55, the upper end of which is recessed or apertured to slide over a rod 56, which is slidably mounted at its opposite ends on the casings of the steam and pump cylinders, respectively. Pivotally mounted intermediate its ends at the side of the steam cylinder 52 is a lever 57, the upper end of which is pivotally connected to the rod 56, as shown at 58. The rod 56 is provided with a stop 59 between which, and the arm 55, is a coil spring 60. A similar stop 61 and a coil spring 62 is provided near the inner end of the rod 56. As the piston rod 54 reciprocates, the arm 55 strikes, alternately, the spring 60 to move the rod 56 in one direction and thereby, through the lever 57, open the steam inlet port 63, and the steam exhaust valve 64, and the spring 62 to move the rod 56 in the opposite direction, and thereby open the steam inlet valve 65 and the steam exhaust valve 66. The exhaust valves are connected with a common exhaust pipe 67. The pump cylinder 53 is provided with inlet valves 68 and 69 connected with a common water-supply pipe 70, and with discharge valves 71 and 72 connected with a common discharge pipe 73, leading to the coils of the generator 1, and provided in its length with a check valve 74. The numeral 75 indicates a pipe for supplying steam to the cylinder 52 for

operating the piston rod 54. The pump is only briefly described as it forms the subject-matter of Patent No. 1,454,331, dated May 8th, 1923, and does not per se enter into the present invention.

The magnet switch 35, heretofore referred to, comprises a casing 76 in which is housed the solenoid 77, surrounding a core 78, normally pressed upward by a coil spring 79. Mounted on the upper end of the core is an armature 80 which has its opposite ends located over contact plates 81 and 82, respectively, connected to lead wires 83 and 84 of an electric circuit including the motor 2. The solenoid 77 is in the circuit formed by the lead wire 84 and another lead wire 85, which includes the magnet 41 of the steam pressure gauge, and the contact 45. The other side of this circuit is a metallic one, the grounded ends of the circuit being indicated, at the steam gauge, by the numeral 86 and adjacent to the battery 34 by the numeral 87. The latter grounded contact is from a lead wire 88 extending direct from the battery 34 to the motor 2. The primary winding of the spark coil 89, is in the circuit formed by a lead wire 90, which includes the stop 49, and a lead wire 91 connecting the primary winding with the main line conductor 83, leading from the motor to the contact plate 81. The numeral 92 indicates the lead wire from the secondary winding of the spark coil connecting to the spark plug 9, the other side of the circuit being a metallic one, as usual, the ground connection being indicated at 93. When the pressure of the fuel reaches a predetermined amount, say, 20 pounds, the arm 48 is lifted by the pin 50 out of contact with the contact member 49, and the spark plug 9 is thus automatically cut out. The pressure of the fuel may continue to build up to, say, 25 pounds, and thereafter pressure is controlled by the solenoid valve 15. That is to say, when the pressure in pipe 21 exceeds twenty-five pounds, the valve 15 will be forced downward against the resistance of spring 16, allowing the fuel to bypass through pipe 13 to the inlet side of pump 4. The control by means of the steam pressure and steam temperature gauges, the automatic cut-out of the spark plug through the fuel pressure gauge, and the control of the fuel pressure by the solenoid valve, are all involved in the combustion system of the patent to Lewis L. Scott, above referred to, and are only briefly indicated herein, in order that the general operation may be better understood.

Referring further to the magnet switch 35, the core 78 is provided with a stem 94 which projects upwardly through the casing 76 and is adjustably connected in the outer end of the lever 95, which is pivotally mounted intermediate its ends at 96 on the

top of the casing 76. Suitably supported on the casing 76 is a valve casing 97, with which communicates the terminal of the steam pipe 75, heretofore referred to as supplying steam to the steam end of the water pump. The numeral 98 also indicates a steam pipe, which leads from the chamber 30 to the valve casing 97, and has its opening into said casing controlled by a valve 99 on the end of a valve stem 100, the upper end of which is adjustably secured toward the outer end of the lever 95. Secured in the extreme outer end of the lever 95 is the upper end of a coil spring 101, the opposite end of which is secured to the casing 97. The hand switch 36, previously referred to, is located in the length of the wire 85, and when this switch is closed the solenoid 77 is placed in circuit with the battery 34, and the armature 80 is drawn into contact with the contact plates 81 and 82, thereby raising the valve 99 so that the steam, when generated, can pass through the pipes 98 and 75 to the steam cylinder 52 and actuate the piston 54, and thereby pump water into the coils of the generator 1. If, for any reason, the coils of the generator should not contain water, at the time it is desired to place the system in operation, the fuel pump 4 can be utilized to pump water into the coils by closing the valves 25 and 28 and opening the valves 24 and 27, as heretofore described. When the switch 36 is closed the circuits to the motor 2, the solenoid 18, and the spark plug 9, will also be closed, and the blower 3 and the fuel pump 4 be placed in operation. Steam is promptly generated by the heat of the ignited spray projected from the nozzle 12 into the combustion chamber of the generator 1, in practice it being found that, starting cold, that is, with no pre-heating whatever, steam sufficient to place the car in operation can be generated in something less than half a minute. The steam for running the engine of the car passes from the chamber 30 through the pipe 29 to the engine, the latter not being shown. The steam also passes from the chamber 30 through the pipe 98, valve casing 97, and the pipe 75 to the steam cylinder 52 and operates the water pump to deliver water through the pipe 73 to the coils of the generator. Should, now, the steam pressure exceed a pre-determined degree, say, 600 pounds, the arm 42^a will be lifted by the pin 46 of the Bourdon tube 40, which will not only break the circuit to the magnet 41, as heretofore described, but will also break the circuit including the solenoid 77, thereby de-energizing the same, whereupon the spring 79 immediately raises the armature 80 out of contact with the contact plates 81 and 82 and breaks the circuit to the motor 2, which, of course, ceases to operate. At the same time the spring 101 will draw the

outer end of the lever 95 downward, forcing the valve 99 to its seat, and preventing the steam from passing to the pipe 75, thereby stopping the water pump. In order to regulate the speed of the water pump, I insert in the pipe 98, a hand valve 102 which may be adjusted to regulate the quantity of steam passing into the cylinder 52. In order to be able to operate the water pump independently of the electric motor, I connect the steam pipes 75 and 98 by means of a pipe 103, which is provided with a valve 104. When the valve 104 is closed the water pump will be controlled in unison with the motor 2 by the magnet switch 35; when the valve 104 is open, however, the steam will pass direct from the pipe 98 to the pipe 75 and thence to the steam cylinder 52, so that the pump will continue to operate so long as there is steam in the generator, irrespective of the fact that the motor may have been cut out by the magnet switch 35.

I claim:—

1. In a steam generating plant for steam automobiles, in combination with a generator for supplying steam to the engine of the car, a liquid fuel burner for heating the generator, a water pump operated independently by steam from the generator for supplying water to the latter, fuel feeding means, an electric motor for actuating the same, and means responsive to generator conditions for automatically controlling the operations of said motor and said pump in unison.

2. In a steam generating plant, in combination with a generator, a liquid fuel burner for heating the same, a water pump operated by steam from the generator for supplying water to the latter, fuel feeding means, an electric motor for actuating the same, an electrically operated device in the circuit of said motor, controlling means for the steam-end of said pump adapted to be actuated by said electrically operated device, and means responsive to generator conditions for opening and closing the circuit of said device whereby to control the operations of the motor and pump in unison.

3. In a steam generating plant, in combination with a generator, a liquid fuel burner for heating the same, a water pump operated by steam from the generator for supplying water to the latter, fuel feeding means, a motor for actuating the same, an electrically operated device in the circuit of said motor, a valve interposed in the steam line to the water pump, means for actuating said valve from said electrically operated device, means responsive to generator conditions for making and breaking the circuit of said device, whereby to automatically control the operations of said motor and said water pump, and a valved by-pass inserted in the steam line of the

water pump for rendering the operation of said pump independent of the control of said electrically operated device at the will of the operator.

5. 4. In a steam generating plant, in combination with a generator, a liquid fuel burner for heating the same, a water pump operated by steam from the generator for supplying water to the latter, fuel feeding means, an electric motor for actuating the same, a magnet switch in the circuit of said motor, controlling means for the steam-end of said pump adapted to be actuated by the armature of said magnet switch, and
- 10 means responsive to generator conditions for opening and closing the circuit of said magnet switch whereby to control the operations of the motor and pump in unison.
- 15 5. In a steam generating plant, in combination with a generator, a liquid fuel burn-

er for heating the same, a water pump operated by steam from the generator for supplying water to the latter, fuel feeding means, a motor for actuating the same, a magnet switch in the circuit of said motor, 25 a valve interposed in the steam-line to the water pump, means for actuating said valve from the armature of said magnet switch, means responsive to generator conditions for making and breaking the circuit of said magnet switch, whereby to automatically control the operations of said motor and said water pump, and a valved by-pass inserted in the steam line of the water pump for rendering the operation of said pump independent of the control of the magnet switch 30 at the will of the operator.

In testimony whereof, I have hereunto set my hand.

EDWARD C. NEWCOMB.
